NONREWIND MACHINE FOR MAGNETIC RECORD MEDIUM

Neel M. Seeburg, Chicago, Ill., assignor to J. P. Seeburg Corporation, Chicago, Ill., a corporation of Illinois

Application August 17, 1945, Serial No. 611,125

5 Claims. (Cl. 28—71.5)

1

This invention relates to a non-rewind machine for wire recording medium and is applicable primarily to machines which will reproduce a recording from such medium repeatedly without the necessity of rewinding the medium after each reproduction.

In order repeatedly to reproduce the recording the medium is continuous and improved means are provided for storing the major part of the medium and means are provided to insure the feeding of the medium through the storage means during reproduction.

This invention is highly advantageous for use with fine wire or filament which presents the special difficulties in the matter of storing a large length of the medium and progressively feeding the medium through the storing means, the wire or filament being very small, for example of the order of three or four thousandths of an inch in diameter.

In accordance with the present invention I provide a high speed rotor and a circumambient stator. The main bulk of the wire is received in helical form between the stator and rotor the spacing of the members being such that any one convolution of the wire cannot pass an adjacent convolution, and at the same time a slight clearance is provided so that any convolution may expand slightly out of effective contact with the rotor.

I prefer to make the rotor and stator in the form of cylinders for ease of manufacture and assembly.

In the preferred embodiment of the invention I provide in the stator a helical recess in which the stored wire is located. As the wire is withdrawn from the storage means the convolutions thereof tend to contract bringing them into effective contact with the rotor. The peripheral speed of the rotor is greater than the speed of the wire so that the wire is fed along the helical recess from supply to discharge ends. In reproduction the wire helix makes slight frictional contact with the rotor so that the wire is fed through the storage means with a certain amount of slippage between the wire helix and the high speed rotor.

The invention will more readily be understood from the following description of a preferred embodiment thereof taken in conjunction with the accompanying drawings, in which:

Figure 1 is an elevational view of a machine embodying my invention;

Fig. 2 is a plan view thereof; and

Figs. 3 and 4 are consequently details illustrating the manner in which the stator and rotor

cooperate with the wire or similar recording medium.

Referring to the drawings the reference numeral 10 designates the recording medium which may, for example, be a steel wire of three or four thousandths of an inch in diameter. This wire is continuous, its ends being welded or otherwise suitably secured together. The wire extends through a pickup magnet 11 of known type which derives signals from the wire in known manner. The bulk of the wire is stored within a helical recess 12 formed on the inner side of a stationary cylinder 13. Within the cylinder 13 is a smooth surface cylinder 14 which is rotatably mounted in bearings 15 and is arranged to be driven at a high speed by means of a pulley 16. The clearance between the two cylinders is quite small and the arrangement is such that the wire cannot move from one convolution of the recess to the next except by its longitudinal movement. A certain degree of play is provided so that the wire may move clear of the rotating cylinder 14 into the recess 12. The upper end (as viewed in Figs. 2, 3 and 4) of the recess 12 extends into a tangential opening 20 in the wall of the cylinder 13 through which the wire may pass outwardly around a pulley 17. The wire passing around the pulley 17 moves over a guide pulley 18, through the magnet 11, around a friction roller 19 and back to the lower end of the recess 12 through a tangential opening 21 in the lower part of the cylinder 13 (as viewed in Fig. 2). The pulley 18 and the roller 19 are arranged properly to locate the wire with relation to the magnet 11. The wire is frictionally engaged between the roller 19 and a roller 22 driven at constant speed by a motor 23. A pulley 24 is driven from the motor 23, this pulley drives the pulley 16 by means of a belt 26. The cylinder 14 is driven in the direction indicated by the arrows and this particular direction requires the recess 12 to be a right-hand helix.

The cylinder 14 is driven at a much higher circumferential speed than is the wire 10 so that the wire within the helical recess 12 is normally moved out of frictional contact with the cylinder 14 towards its position shown in Fig. 3. In reproduction the drive of the wire effected by the rollers 19 and 22 draws the wire out of the cylinder 13 through the opening 20 causing the wire within the upper part of the recess 12 to move into engagement with the high speed rotor 14. Consequently the rotor 14 moves the wire upwardly through the helical recess 12, all of the wire within the recess 12 moving into engage-

ment with the surface of the cylinder 14. Thus if the wire in Fig. 3 were drawn out to bring the upper part (as viewed in that figure) of the wire in the recess 12 into engagement with the cylinder 14 as shown in Fig. 4, the rotation of this cylinder would move the wire upwardly (as viewed in that figure) until the upper part was out of effective frictional engagement with the cylinder 14. The upward movement of the wire would contract lower convolutions thereof so that the wire in those convolutions would be moved upwardly and so on until all the wire in the cylinders was moved up bodily and all the wire in the recess 12 was out of effective frictional contact with the cylinder 14. In reproduction the wire is withdrawn from and supplied to the recess 12 at a uniform rate and all the wire in the recess 12 makes slight frictional contact with the cylinder 14 so that the wire is fed upwardly through the recess 12 at a uniform speed which is considerably lower than the speed of the surface of the cylinder 14. In other words the feed is uniform and there is a considerable degree of slippage between the wire and the surface of the cylinder 14. If there is an isolated contraction of the wire helix, the contracted convolutions are snubbed to the cylinder 14 so that the contraction is immediately relieved.

In order to accommodate wire of slightly varying lengths, it is preferred to mount the spindle of the pulley 17 on a carriage 27 which is adjustably mounted on a slide 28. Proper adjustment of the carriage 27 provides a small degree of slack in the medium, which slack is normally accommodated between the rotor and stator during operation.

Although the invention has been described in connection with specific details of a preferred embodiment thereof it must be understood that the same are not intended to be limitative of the invention except in so far as set forth in the accompanying claims.

Having thus described my invention I declare that what I claim is:

1. In a machine for magnetic recording medium, a storage mechanism comprising a high speed rotor and a stator surrounding said rotor and maintaining a space therebetween to receive a helix of said medium, said stator being provided with a helical recess to receive said medium, the space between the stator and rotor being sufficiently small to prevent one convolution of the medium from passing from one convolution of the recess to an adjacent convolution of the recess except by axial movement, said recess being sufficiently deep to permit the medium to move out of contact with the rotor.

2. In a machine for magnetic recording medium, in combination, storage mechanism comprising a high speed rotor and a stator surrounding said rotor and maintaining a space therebetween to receive a helix of said medium, the space between the rotor and stator being sufficiently small to prevent one convolution from passing an adjacent convolution, and sufficiently large to permit the medium to move out of contact with the rotor, and means for withdrawing said medium from said storage mechanism at a speed lower than the peripheral speed of the rotor whereby the helix is contracted in the radial direction and snubbed on to the high speed rotor and fed thereby in the helical direction to point of withdrawal.

3. In a machine for magnetic recording me-

dium, in combination, storage mechanism comprising a high speed rotor and a stator surrounding said rotor and maintaining a space therebetween to receive a helix of said medium, a helical recess in said stator adapted to receive said helix, the space between the rotor and stator being sufficiently small to prevent a convolution of the helix from passing from a convolution of the recess to an adjacent convolution except by axial movement of the medium, said recess being sufficiently deep to permit the medium to move out of contact with the rotor, and means for withdrawing said medium from said storage mechanism at a speed lower than the peripheral speed of the rotor whereby the helix is contracted in the radial direction and snubbed on the high speed rotor and fed thereby in the helical direction to the point of withdrawal.

4. In a machine for continuous magnetic recording medium, in combination, storage mechanism comprising a high speed rotor and a stator surrounding said rotor and maintaining a space therebetween, an endless length of medium having its major portion located in the space between the stator and rotor in the form of a helix and a minor portion or loop to the exterior of said stator, the space between the rotor and stator being sufficiently small to prevent one convolution of the helix from passing an adjacent convolution and sufficiently large to permit the medium to move out of contact with the rotor, exterior means for moving the loop and thereby withdrawing medium from the storage mechanism at a speed lower than the peripheral speed of the rotor whereby the helix is contracted in the radial direction and snubbed on to the high speed rotor and fed thereby in the helical direction to the point of withdrawal.

5. In a machine for continuous magnetic recording medium, in combination, storage mechanism comprising a high speed rotor and a stator surrounding said rotor and maintaining a space therebetween, an endless length of medium having its major portion located in the space between the stator and rotor in the form of a helix and a minor portion or loop to the exterior of said stator, a helical recess in said stator adapted to receive said helix, the space between the rotor and stator being sufficiently small to prevent a convolution of the helix from passing from a convolution of the recess to an adjacent convolution except by axial movement of the medium, said recess being sufficiently deep to permit the medium to move out of contact with the rotor, exterior means for moving the loop and thereby withdrawing medium from the storage mechanism at a speed lower than the peripheral speed of the rotor whereby the helix is contracted in the radial direction and snubbed on to the high speed rotor and fed thereby in the helical direction to the point of withdrawal.
